UNITED STATES PATENT OFFICE.

CASSIUS P. BYERS, OF VELVA, NORTH DAKOTA.

SMOKE-STACK.

No. 926,167.

Specification of Letters Patent.

Patented June 29, 1909.

Application filed April 1, 1908. Serial No. 424,546.

To all whom it may concern:

Be it known that I, CASSIUS P. BYERS, a citizen of the United States, residing at Velva, in the county of McHenry, State of North Dakota, have invented certain new and useful Improvements in Smoke-Stacks; and I do hereby declare the following to be a full, clear, and exact description of the invention, such as will enable others skilled in the art to which it appertains to make and use the same.

This invention relates to smoke stacks and more particularly to the class which are so constructed as to prevent the emission of cinders and sparks therefrom.

In carrying out my invention, I inclose the upper end of the smoke stack within a hood which is of two-part construction the lower half of the hood having spark conducting and collect-pipes extended from its lower end and provided at their lower ends with movable closures whereby the cinders may be permitted to discharge from the pipes, the upper half of the hood being provided interiorly with an annular deflector the smaller end of which is located directly above the upper end of the smoke stack. Suspended from the said end of the deflector is an inverted conical foraminous deflecting element preferably formed of wire mesh material and this element projects downwardly into the upper end of the stack. In the lower section of the hood are formed openings which are covered by sheets of wire mesh material and similar openings or vents are formed in the upper section above the deflector, these openings aiding in the creation of a circulation within the stack.

In the accompanying drawings, Figure 1 is a vertical sectional view through the upper end of a smoke stack constructed in accordance with my invention. Fig. 2 is a similar view but taken in a plane at right angles to the plane of Fig. 1. Fig. 3 is a top plan view of the stack. Fig. 4 is a horizontal section on the line 4--4 of Fig. 1. Fig. 5 is a horizontal section on the line 5--5 of Fig. 1. Fig. 6 is a horizontal section on the line 6--6 of Fig. 1. Fig. 7 is a detail in perspective of the upper end of the stack showing the cinder collecting and conducting pipes herein-after referred to.

In the drawings, the stack proper is indicated by the numeral 10 and is provided with an upper flared end 11. As has heretofore been stated, the said upper flared end 11

of the stack is inclosed in a hood and this hood is formed of two sections, the lower section being indicated in general by the reference character A and the upper section by 60 the reference character B. The lower section A is secured directly to the stack and has its body portion 12 of the same general outline as the flared upper end of the stack, the wall of the body portion and the wall of 65 the flared upper end of the stack being spaced with respect to each other and the upper edge of the section A being terminated in a horizontal plane with the upper edge of the flared upper end 11 of the stack 70 and being formed with a flange 13. The upper section B of the hood is substantially frusto-conical in shape and is formed at its lower edge with a flange 14 which is disposed against the flange 13, there being bolts 15 75 passed through the two flanges for the purpose of securing the upper section B in position upon the lower section A of the hood.

A deflector 16, which is substantially of inverted frusto-conical form, is secured at its 80 upper or major end to the wall of the upper section B of the hood and within the said section and is disposed with its smaller end down, the said smaller end of the deflector being located substantially in the same 85 plane as the upper edge of the flared upper end 11 of the smoke stack. An inverted conical foraminous deflecting element 17 is provided at its upper or major end with a threaded flange 18 which is threaded into a 90 similar flange 19 formed at the lower or minor end of the deflector 16, the conical foraminous deflecting element being in this manner detachably connected with the deflector 16 so that it can be removed and 95 cleaned when found necessary.

Leading from the lower or minor end of the body 12 of the lower section A of the hood and extending downwardly along opposite sides of the smoke stack 10 are cinder 100 collecting and discharge tubes 20, to the lower ends of which are hinged doors 21 which may be swung upon their hinges to permit of discharge of the cinders from the said pipes, it being understood that the cinders are directed against the foraminous and the impervious deflectors 17 and 16 respectively and downwardly between the walls of the flared upper end 11 of the smoke stack and the lower section A of the hood inclosing the 110 same, and that the said cinders settle into the pipes 20 and collect therein until such time

as the doors 21 are opened, the doors being normally held closed by means of suitable latches 22. The smoke, freed of the sparks and cinders, passes through the foraminous deflector 17 and out through the upper end of the upper section B of the hood.

Formed at diametrically opposite points through the walls of the lower section A of the hood are openings 23 which are covered 10 by sheets of foraminous material 24, these coverings preventing sparks and cinders being discharged from the openings but permitting of draft through the openings to aid in the establishment of a circulation within the 15 stack and hood. In order that the size of the openings 23 in the lower section A of the hood may be varied according to the fuel used and its condition, imperforate slides, preferably of sheet metal, indicated by the 20 numeral 25, are arranged for movement into position to close or to expose the said openings 23, these slides being of course arranged upon the outer side of the said section A so that they may be moved by hand. Similar 25 openings or vents 26 are formed in the section B of the hood in a plane above the deflector 16 and these vents also aid in the establishment of a circulation within the hood and stack.

30 What is claimed, is:—

1. The combination with a smoke stack having an inverted frusto conical mouth, of a

hood over the mouth thereof, an inverted frusto conical deflector in the hood above the mouth of the stack, a threaded cylindrical portion formed on the lower end of said deflector, and an inverted conical strainer provided with a threaded rim adapted to be held in the threaded portion of the deflector, said strainer having its sides parallel with the 40 mouth of the stack.

2. The combination with a smoke stack having an inverted frusto conical mouth and a sectional hood having an inverted frusto conical lower portion surrounding said 45 mouth and a frusto conical upper portion extending thereabove and over the mouth of the stack, an imperforate deflector of inverted frusto conical shape arranged within the upper section of the hood over the mouth of the stack, a threaded cylindrical flange on the lower end of said deflector, and an inverted conical strainer provided at its upper 50 end with a threaded rim adapted to engage the threaded flange of the deflector, said 55 strainer, mouth of the stack, and the lower portion of the hood being parallel.

In testimony whereof, I affix my signature, in presence of two witnesses.

CASSIUS P. BYERS.
